UNITED STATES PATENT OFFICE.

LOUIS A. CASGRAIN, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

WORK-SUPPORT-CONTROLLING MECHANISM.

1,279,512.

Specification of Letters Patent. Patented Sept. 24, 1918.

Application filed January 28, 1915. Serial No. 4,936.

To all whom it may concern:

Be it known that I, LOUIS A. CASGRAIN, a citizen of the United States, residing at Beverly, in the county of Essex and State of Massachusetts, have invented certain Improvements in Work-Support-Controlling Mechanism, of which the following description, in connection with the accompanying drawings, is a specification, like reference characters on the drawings indicating like parts in the several figures.

This invention relates to work supports and to work support controlling means which are particularly adapted for machines which are used in the manufacture of boots and shoes and is herein shown as embodied in a construction comprising a work support of the jack type employed in connection with a machine for inserting fastenings. It will be understood, however, that the invention is applicable to other types of machines and is capable of utilization in connection with other types of work supports.

The machine in which the invention is herein shown as incorporated is particularly adapted for inserting slugs or fastenings in the top lifts of the heels of boots or shoes, the operation which requires for its successful performance substantial uniformity in the work presenting operations. In such machines the work is usually clamped between the work support and a work abutment at the time the fastening is inserted, and between the successive fastening inserting operations a relative releasing movement of the work support and the work abutment takes place, mechanism being generally provided for making this releasing movement uniform regardless of differences in the amount of separation of the work support and the work abutment as the work varies in thickness. This mechanism ordinarily comprises a spring by which the relative movements of the work support and its releasing mechanism that are necessary to accommodate the variations in dimensions of the clamped work are effected, the spring aiding usually in moving the work support again into work clamping relation to the work abutment. To insure uniformity of the clamping action between the work support and the work abutment it is desirable

that the range of compression of this spring shall not be too great, and, moreover, it is found to be desirable not to attempt to provide, in the automatic compensating adjustment of the work support releasing mechanism, for the accommodation of a very great range of variations in the heights or thicknesses of the different pieces of work to be operated upon, since thereby the efficiency of the operation of this mechanism is likely to be seriously reduced.

In machines of this kind provision is usually made for an adjustment of the work support upon its carrier so that when the work is clamped the position of the work support carrier may be kept within comparatively narrow limits. It has been necessary heretofore to effect this adjustment by hand and, when inserting slugs or other fastenings in the heels or in the heel seats of shoes on the last, proper presentation of the work and proper release for feeding has required frequent adjustment of the work support upon its carrier owing to the lack of uniformity in the positions, depths and conditions of the last pin holes in the lasts, to differences in the heights of heels, to differences in the heights of lasts and to other causes tending to a lack of uniformity in the work.

Because of the inconvenience and undesirability of the above described adjustment of the work support, it has been the practice heretofore to make this adjustment only when about to operate upon shoes of a different style or when the shoes were upon lasts of a different type or height or were of a markedly different size. The operator has usually, therefore, made this adjustment of the work support only when starting upon a new case of shoes, with the result that the slugging or fastening inserting operation has been affected in its quality more or less by reason of improper support of the work due to the variations in the work, above pointed out.

An important object of the present invention is to provide means for adjusting the work support to adapt it to the different variations in the work, above mentioned, which will operate automatically and will effect the adjustment of the work support for each piece of work.

Another object of the invention is to provide improved work support adjusting means which will be of general utility where conditions similar to those described above are present.

An important feature of the invention is the construction and arrangement of the work support adjusting means so that an initial adjustment of the work support upon its carrier is effected to adapt it to the particular piece of work to be operated upon and the work support is then locked to its carrier in this adjustment. After work clamping relationship has been established between the work support and the abutment the control of the work support is left to automatic controlling means of the general type employed in such machines while the machine is performing the series of operations which are to be performed upon this piece of work.

Another important feature of the invention is the provision of means for locking a work support thus adjusted to the machine frame, whereby an accurately adjusted, rigid support for the work is provided for each inserting operation.

Other objects and important features of the invention will appear from the following description and claims when considered in connection with the accompanying drawings, in which,—

Figure 1 is a side elevation of a slugging machine in which a work support embodying the present invention has been incorporated;

Fig. 2 is a detached perspective of the work support and a portion of the connections by which the automatic adjustment is controlled;

Fig. 3 is a longitudinal section through the locking mechanism;

Fig. 4 is a perspective detail showing the principal elements of the locking mechanism in separated relation;

Fig. 5 is a perspective view of the mechanism for intermittently depressing the work support; and

Fig. 6 is a perspective view of the eccentrically mounted fulcrum for the lock operating bell-crank, said fulcrum being removed from its bearings.

The slugging machine in which this invention is shown as incorporated is of the type illustrated and described in United States Letters Patent to L. A. Casgrain, No. 1,053,479, granted February 18, 1913, and comprises, as more fully set forth in said Letters Patent, a base or standard 10 which supports a head 12 in which is journaled the main driving shaft 14, from which a cross shaft 114 is driven by a worm and gear connection, not herein shown. From this cross shaft, as more fully set forth in said Letters Patent, the starting and stopping of the fastening inserting operation is controlled and

the movement of the various elements of the fastening inserting mechanism into and out of operative relation to each other is effected. From a cam groove 192 in a cam disk upon the side of the machine remote from that viewed in Fig. 1 a lever arm 188 is caused to rock a rock shaft 186 which controls the movement of the awl 162 into and out of operative relation to the inserting mechanism. The awl 162, when in operative position, is swung laterally with a swinging head to feed the work. Upon the cross shaft 114 is carried a cam, more fully shown and described in said Letters Patent, by which the work support carrier is raised into its operative position before the beginning of the fastening inserting operation.

The illustrated work support, as hereinabove suggested, is of the jack type, and comprises a spindle 20 in the upper end of which is adjustably secured in a well-known manner a last pin holder 22 carrying a last pin 24. The spindle 20 at its lower end is secured by a set screw 25 (Fig. 2) to a pivot pin 26 having bearings in ears 28 of a rocker foot 30, said rocker foot being of the type illustrated and described in United States Letters Patent to W. H. Cuff, No. 919,424, granted April 27, 1909, and being provided with teeth 32 which mesh with corresponding teeth 34 in a rocker bed 36 carried by a slide 38 arranged to slide vertically in guides 40 in a depending portion of a bracket 42 having at its upper end a sleeve 44 which is clamped upon the horn or jack post 46 by clamping screws 48. A bolt 50 passing through an enlarged opening in the rocker foot 30 prevents the complete separation of the rocker foot 30 from the bed 36. The slide 38 is provided below the bed 36 with teeth 52 with which operate two dogs or pawls 54, 56, the pawl 54 being wider than the pawl 56, and being slotted at 58 to receive the pawl 56, the two pawls being pivoted upon a common pivot pin 60. The teeth of the pawls 54 and 56 are so inclined that they tend to operate in opposite directions so far as their locking action is concerned. The purpose of providing two pawls, which serve to lock the jack to the jack post against relative movement thereof in either direction, is to insure the movement of the jack away from the work abutment during the work releasing operation, as well as to provide a positive connection to the jack post to receive the impact of the fastening inserting operation. Springs 62 coiled about a pin 64 extending between the sides 66 of the slide receiving portion of the bracket 42 act at one end upon the upper portion of the pawl 54 and force its tooth toward the ratchet teeth 52, and at their other ends upon the tail 68 of the pawl 56 to force its tooth also toward the ratchet teeth 52 upon

the slide 38. The tail 68 of the pawl 56 has upon its under side a bevel face 70, and the tail portions 72 of the pawl 54 have upon their rear faces bevel portions 74, the bevels 70 and 74 being so related to each other that they may be engaged substantially simultaneously by the pawl disengaging member 76 adjustably connected to the front end of a lever 78 by a bolt 80 having a shouldered nut 82 received in a slot 84 in said member 76. At its rear end the lever 78 is connected by a link 86 to an arm 90 upon the rock shaft 186 of the awl controlling mechanism hereinabove described.

In Fig. 1 of the drawings the parts are shown in the position which they assume just before the machine is actuated to insert the fastenings, the awl 162 being drawn back into its inoperative position and the jack spindle 20 being held yieldingly in work clamping position by springs 92 connected at their lower ends to bolts 94 upon the rocker bed 36, and at their upper ends to pins 96 on the bracket 42. It will be noted that in this figure the pawl disengaging member 76 is located between the tails of the pawls, and the pawls are disengaged from the ratchet teeth 52. When the machine is to be rendered operative to insert the fastenings, as more fully described in the Letters Patent above referred to, the shaft 114 has imparted to it a half turn and as it turns it operates to raise the jack post 46, thereby through the bracket 42 raising the pawls 54 and 56 until their tails 68 and 72 are moved out of releasing relation to the member 76, when the pawls will engage the ratchet teeth 52, thus locking the jack in the position of adjustment with respect to the jack post 46 in which it has been held by the springs 92 and causing the jack to partake thereafter of the movements of the jack post.

In this machine, as in the machine of the Letters Patent above referred to, the work support is automatically depressed between the successive fastening inserting operations to permit the work to be fed easily into position to receive the succeeding fastening, and means is provided for automatically bringing to bear upon the work support the clamping pressure of a strong spring before the fastening inserting mechanism is rendered operative to insert fastenings and for removing this pressure and lowering the post 46 after the inserting mechanism has been rendered inoperative. The mechanism for effecting the initial raising and final depression of the post 46 is substantially identical with that of the Letters Patent hereinabove referred to, and comprises a cam upon the end of the shaft 114 remote from that shown in Fig. 1, which cam is given a half turn to raise the post 46 when the inserting mech-

anism is rendered operative, as more fully described in said Letters Patent. The mechanism for intermittently depressing the work support to release the work for feeding is of the type of that shown in Letters Patent No. 1,108,133, August 25, 1914, L. A. Casgrain, and is illustrated sufficiently for the purposes of the present disclosure in Figs. 5 and 6 of the drawings.

Referring to Figs. 1 and 5, the jack post 46 rests upon a support 460 to which the upper link 462 of a toggle is pivotally connected, the support 460 comprising a stud or spindle 464 which projects up into the hollow interior of the post 46. The lower link 470 of the toggle is pivotally connected to a slide 440. To lower and raise the work support, means is provided for breaking and straightening the toggle, the illustrated means comprising a rod 472 pivotally connected at one end to the knee joint 474 of the toggle and at its other end pivotally connected to one arm of the bell crank lever 476 fulcrumed at 478 in the base of the machine. The other arm of the bell crank lever 476 is pivotally connected to a rod which is connected at its other end to a lever 221 rocked by a face cam in the driving pulley 16, as more fully shown and described in said Letters Patent No. 1,108,133.

Means is provided for locking the slide 440 against movement by the spring 268, more fully shown and described in said Letters Patent No. 1,108,133, when the toggle is broken, and also for locking the slide 440, when the toggle is straightened, to provide a rigid support for the work during the fastening inserting operation. The illustrated means comprises a plurality of locking plates 480 spaced from each other and attached by the rivet 482 to the slide 440, the plates 480 alternating with a second set of locking plates 484 attached to and carried by the casing 442. The illustrated means for pressing the respective sets of plates into locking engagement with each other differs slightly from that shown in said Letters Patent No. 1,108,133, and comprises a sliding bolt 492 having in its rear end a notch 493 wider at its open end than at its bottom, a tooth 494 upon the upper end of a bell crank 495, fulcrumed upon an eccentrically mounted fulcrum 491, being arranged to be moved into engagement with said notch 493, whereby said bolt 492 may be moved into and out of operative locking relation to the plates as said bell crank is rocked upon its fulcrum. The bell crank 495 has connected to its other arm a rod 496 which is pivotally connected at its upper end to a lever 497 rocked by a cam groove 498 in a cam disk 499 upon the end of the main driving shaft 14 of the machine. The movement of the lever 497 is transmitted by the rod 496 to the bell crank 495, and the bolt 492 is moved into and out of operative locking relation to the plates as the bell crank 495 is rocked upon its fulcrum.

492 is thus moved in proper time relation to the straightening and breaking of the toggle 462, 470.

When the tooth 494 upon the bell crank 495 is in the position shown in Fig. 5 of the drawings, the movement of the bell crank is not transmitted to the bolt 492, although the bell crank is constantly rocked by reason of its connection with the constantly rotating main shaft 14. To move the tooth 494 into operative relation to the notch 493 at the proper time in the operation of the machine, means is provided for turning the eccentrically mounted fulcrum 491 in its bearings, the illustrated means comprising a crank arm 500 clamped upon the extension 501 of the concentric portion of the fulcrum member 491, said crank arm being provided at its outer end with a wrist pin 502 which 10 is connected by a link 503 to an arm 504 rigidly clamped upon the rod 264 by which the work support is automatically raised into work supporting position when the machine is started, as more fully set forth in 15 said Letters Patent No. 1,108,133, above referred to. When the machine is to be rendered operative for inserting fastenings, the rod 264 is automatically depressed to rock the lever 224 and raise the work support, bringing to bear upon the work support the clamping pressure of the spring 268, and this downward movement of the rod 264 turns the crank 500 in a counter-clockwise direction in Fig. 5, and raises the eccentrically mounted fulcrum of the bell crank 495 so that the tooth 494 comes into operative relation to the notch 493.

The springs 92, which effect the automatic adjustment of the jack with respect to the 20 jack post, are preferably of such length and of such strength that, when the jack post 46 is in its lowered position, these springs will press the work against the foot plate or work abutment 351 with a light yielding pressure, sufficient, however, to insure the quick adjustment of the jack to the thickness of the work. As the jack post is raised before the inserting mechanism is rendered operative, the tension on the springs 92 will 25 be increased, thus insuring the maintenance of the work against the foot plate 351 until the pawl disengaging member 76 has been moved out of engagement with the tails of the pawls and has thus permitted the pawls 30 to lock the slide 38 to the bracket 42. The spring 268 is preferably of such strength compared with the springs 92 that, in the initial work support adjusting operation, substantially no compression of the spring 268 takes place before the work support is 35 locked to its carrier.

The operations of the various elements of the work support controlling and adjusting mechanism have been described in connection with a detail description of these ele-

ments, but for the sake of clearness the operation of the mechanism as a whole will now be described.

The parts being in the position shown in Figs. 1 and 2, the operator places the last 40 upon the last pin 24 thereby depressing the jack against the tension of the springs 92, these springs, as hereinabove set forth, being strong enough to hold the top lift 45 lightly against the foot plate 351 so that 45 the operator can easily locate the shoe in proper relation to the gage or gages usually provided in machines of this type. The operator now manipulates the manual control of the actuating mechanism, more fully described in Letters Patent No. 1,053,479, hereinabove referred to, thereby causing the 50 shaft 114 to be connected to the constantly rotating shaft 14. Turning of the shaft 114 through a half rotation operates, 55 through connections to the lever 224, to raise the jack post 46, said connections comprising the rod 264 and the spring 268 which is compressed to place spring pressure upon the jack post as soon as the upward movement of the jack post is prevented by the locking of the jack to the jack post and the clamping of the work, the rod 264 then moving relatively to the lever 224. As the jack 60 post moves upward it carries with it the pawls 54, 56, and the tails of the pawls are thus moved out of engagement with the pawl releasing member 76 shortly after the upward movement of the jack post begins. In the illustrated machine substantially a 65 quarter of the total movement which would be imparted to the jack post, were it entirely free to move, is utilized in moving the pawls 70 out of engagement with the releasing member 76, so that the balance of said movement 75 of the jack post raising mechanism is utilized in compressing the spring 268 to clamp the work under spring pressure. After the 80 pawls are permitted to move into engagement with the ratchet plate to lock the jack 85 to the jack post and after the clamping pressure has been placed upon the work, the sliding bolt 492 is moved in the direction to cause the plates 480 to be locked to the 90 plates 484, the eccentric fulcrum 491 for the bell crank 495 having been turned during 95 the jack post raising operation by the connections to the rod 264, comprising the arm 500, the link 503 and the arm 504. At this 100 time the toggle 462, 470 is substantially in 105 straightened condition, a slight straightening movement following the clamping together of the plates 480 and 484 to apply to 110 the work a further clamping pressure.

The machine now operates to insert a fastening and, after the awl has entered the work to form an opening to receive the next fastening and before it starts to move in the direction to feed the work, the rod 472 is moved in the direction to break the toggle 120 125 130

- 462, 470 to lower the jack post, the plates 480, 484 being maintained at this time in locking relation to each other whereby they prevent the spring 268 from acting upon the 5 jack post during the work releasing operation. As the toggle is again moved toward straightened position the sliding bolt 492 is drawn back to unlock the plates 480, 484 to permit the spring 268 to coöperate in adjusting the work support to the work in the 10 event that the thickness of the work at the point at which the succeeding fastening is to be inserted is greater or less than that previously clamped. In the event that the 15 thickness of the work should increase considerably, thus tending to bring the jack post into such position that the pawls 54, 56, during the work releasing movement of the jack post, might move into engagement with 20 the pawl releasing member 76, thus causing a new adjustment of the jack upon the jack post, means has been provided for moving the pawl releasing member 76 out of the range of movement of the pawls as the machine is rendered operative to insert fastenings in order to prevent unnecessary 25 adjustments of the jack upon the jack post while the machine is operating upon the piece of work for which it has been initially 30 adjusted. Although such adjustments would not effect the quality of the work, they are objectionable in that they tend to wear the parts needlessly. The means for moving the member 76 out of the path of movement of 35 the pawls at this time has been hereinabove described, and comprises the lever 78, link 86 and arm 90 upon the rock shaft 186. As the awl 162 is moved into operative position by the rocking of the rock shaft 186 the arm 40 90, through its connections to the lever 78, moves the member 76 out of the path of movement of the pawls 54, 56.
- Having fully described my invention, what I claim as new and desire to secure by 45 Letters Patent of the United States is:
1. In a machine of the class described, which comprises mechanism for performing a series of operations upon work, and means for effecting a relative feeding movement 50 of the work and said mechanism between successive operations, the combination with a work support comprising members relatively movable to adjust the support to different work thicknesses, of means for automatically effecting such relative movement and locking said members in the position of adjustment for said series of operations before said operating mechanism begins to operate upon the work.
  2. In a machine of the class described, comprising mechanism for intermittently operating upon the work, and means for feeding the work between said operations, the combination with a work support and 55 means, including work thickness compensat-
- ing mechanism, for depressing the work support to permit the work to be fed freely, of means for automatically effecting an initial adjustment of said work support to the thickness of the work before the operating 70 mechanism is rendered operative, and means for maintaining said adjustment while the machine continues to operate upon a piece of work for which the adjustment has been effected. 75
3. In a machine of the class described, a work support, a work abutment, means operating to cause said work support normally to clamp the work against said work abutment when the machine is operative, means comprising work thickness compensating means for effecting a uniform release of the work from the clamping pressure between successive operations of the machine thereon, and means for automatically effecting an initial relative adjustment of the work support and its operating means to the thickness of the work to secure substantial uniformity of clamping pressure upon different 80 pieces of work. 85
  4. In a machine of the class described, the combination with a work abutment, a work support and controlling means operating between successive operations of a series performed upon a single piece of work 90 to effect relative work releasing and work clamping movements of said support and said abutment, of means, governed in its operation by the clamping of the work for the initial operation of the series, for automatically effecting a relative adjustment of 95 said work support and said controlling means for the series of operations upon that piece of work. 100
  5. In a machine of the class described, a work support, a carrier for said work support, connections between said parts whereby they are normally yieldingly maintained in extended relation, a work abutment, means acting upon said carrier for automatically bringing said carrier into predetermined relation to said abutment whereby a yielding relative movement of said work support and said carrier is effected, means for automatically locking said work support to said carrier in the relation which said parts assume at the end of said relative movement, and means for thereafter effecting final work clamping relationship between 110 the work support and the abutment. 115
  6. In a machine of the class described, a work support, a carrier for said work support upon which said work support is slidably mounted, spring connections between said work support and said carrier tending to maintain said parts normally in extended relation, a coöoperating work abutment, means for moving said carrier into predetermined relation to said abutment, means operating 125 automatically to lock said work support to 130

- 5 said carrier in the adjusted relation to which said parts are thus moved, and means for thereafter moving said parts together while a series of operations is being performed 5 upon the work for which they have been initially adjusted.
7. In a machine of the class described, which comprises mechanism for performing a series of operations upon work and means 10 for effecting a relative feeding movement of the work and said mechanism between successive operations, a work support, a carrier for said work support, connections between said work support and said carrier whereby 15 said parts are normally yieldingly maintained in extended relation, a work abutment, means for bringing said carrier into predetermined relation to said work abutment whereby a relative movement of said 20 carrier and said work support is effected, means for locking said work support rigidly to said carrier in the relation which these parts assume at the end of said relative movement, and means for automatically effecting a movement of depression of said 25 carrier and work support, of uniform extent, between the successive operations upon the work.
8. In a machine of the class described, 30 which comprises mechanism for performing a series of operations upon work and means for effecting a relative feeding movement of the work and said mechanism between successive operations, a work support, a carrier for 35 said work support upon which said work support is adjustably mounted, a work abutment, means operating automatically before the series of operations upon the work begins for effecting an adjustment of said work 40 support upon its carrier with respect to the work gaged between said support and said abutment and for locking said work support rigidly to said carrier after said adjustment has been effected, and means operating 45 automatically to effect an adjustment of said rigidly connected work support and carrier with respect to said abutment after each operation upon the work and for locking said carrier against movement for the succeeding 50 operation upon the work.
9. In a machine of the class described, which comprises mechanism for performing a series of operations upon work, a work abutment, a work support comprising relatively 55 movable members, means for effecting a movement of said work support into operative work supporting relation to said abutment, constructed to cause a relative movement of said members whereby said work 60 support is adjusted to the thickness of the work, means for locking said members together after such adjustment, and means for locking said work support against bodily movement before each operation upon the 65 work.

10. In a machine of the class described, which comprises mechanism for performing a series of operations upon work, a work abutment, a work support comprising relatively movable members, means for effecting a movement of said work support into operative work supporting relation to said abutment, constructed to cause a relative movement of said members whereby said work support is adjusted to the thickness of the work, means for locking said members together after such adjustment, means for effecting a bodily movement of said work support to release the work and again clamp it after each operation upon the work, constructed to effect always the same amount of movement of said work support, and means for locking said work support against bodily movement before the succeeding operation upon the work. 75 80 85

11. In a machine of the class described, the combination with a work support, comprising relatively movable members, and work support releasing mechanism constructed to effect a uniform releasing movement of the work after each operation thereon, of means for effecting automatically a relative movement of adjustment of the members of said work support before the initial operation upon the work and for locking said members in their position of adjustment. 90 95

12. In a machine of the class described, in combination with the machine frame, a work support, a carrier for said work support upon which said support is adjustable, means for effecting a predetermined movement of said carrier to move said work support into work supporting position and for causing an adjustment of said work support upon said carrier in proportion to the thickness of the work, means for locking said work support to said carrier in the adjusted relation, and means for locking said carrier to the machine frame. 100 105 110

13. In a machine of the class described, the combination with the machine frame, a work abutment, and a work support, of a carrier for said work support upon which said work support may be adjusted to suit it to the thickness of the work, means for imparting a predetermined movement to said carrier and for simultaneously effecting the adjustment of said work support upon said carrier, means for locking said work support to said carrier in the adjusted relation, means whereby said work support is caused to clamp the work against the work abutment, and means for locking said support in work clamping relation. 115 120 125

14. In a machine of the class described, the combination with the machine frame, a work abutment and work supporting means, said abutment and said work supporting means being relatively movable into 130

- work caliper relation to each other, and said work supporting means comprising members relatively movable to adjust said support to the thickness of the work, of means for automatically effecting said relative movements, and means operating automatically to lock said members of said support together in adjusted relation and to lock said support to the machine frame.

15. In a machine of the class described, the combination with the machine frame, a work abutment and work supporting means, said work supporting means comprising members normally yieldingly maintained in extended relation, of means acting automatically to effect a relative work clamping and work caliper movement of said abutment and said work supporting means, constructed to effect, by reason of the interposition of the work, a relative movement of said members to adjust said supporting means to the thickness of the work, and means acting automatically to lock said members together in their adjusted relation and to lock said work support to the machine frame.

20. In a machine for performing a series of operations upon a piece of work which is moved relatively thereto, a work support, a carrier upon which said work support is self-positioning to suit it to the general characteristics of the work, means operating initially to move the carrier relatively to the work support, means operating automatically to lock said support to the carrier in adjusted position before said series of operations begins, and means operating automatically to move the carrier to release the work for feeding movement thereof between the successive operations.

25. In a machine for performing a series of operations upon a piece of work which is moved relatively thereto, a work abutment, a work support, a carrier upon which said work support is self-positioning to suit it to the thickness of the work, said work support being movable to present the work to the machine, means operating automatically to lock said support to said carrier in adjusted relation and means for thereafter bringing said parts into work clamping relation to said abutment.

30. In a machine for performing a series of operations upon a piece of work which is moved relatively thereto, a work support, a carrier for said work support, yielding connections between said carrier and said work support whereby said work support may adjust itself to the thickness of the work as the work is presented to the machine, and means operating automatically to lock said work support to said carrier before the series of operations begins, constructed to maintain said parts in the adjusted relation during the series of operations.

35. In a machine for performing a series of operations upon a piece of work which is moved relatively thereto, a work support, a carrier for said work support, yielding connections between said carrier and said support to permit initial relative adjusting movement of the work support and the carrier, means operated by movement of said carrier relatively to said work support before said series of operations begins to lock said work support automatically to the carrier, and means for thereafter moving said work support and carrier together during said series of operations.

40. In a machine for performing a series of operations upon a piece of work which is moved relatively thereto, a work abutment, a work support yieldingly held normally substantially in work presenting relation to said abutment, a movable carrier for said work support upon which said work support is yieldingly adjustable as the work is interposed between said abutment and said support, and means rendered operative by initial movement of said carrier for locking said support to said carrier in adjusted position, said means being constructed and arranged to maintain said carrier and said work support locked in adjusted relation during the series of operations.

45. In a machine of the class described, a work abutment, a work support, a movable carrier for said work support upon which said work support is yieldingly adjustable as the work is interposed between said abutment and said support, means rendered operative by the movement of said carrier for locking said support to said carrier, and means, comprising a spring, for effecting such movement and bringing clamping pressure to bear upon the work.

50. In a machine of the class described, in combination with the machine frame, a work support, a carrier for said work support, yielding connections between said carrier and said work support whereby said work support may be adjusted upon said carrier by the presentation of the work, means rendered operative by a relative movement of

5
said carrier and said support for locking said support to said carrier, and means co-operating with the machine frame for thereafter locking said support rigidly against movement.

24. In a machine of the class described, a work abutment, a work support, a movable carrier for said work support upon which said support is yieldingly movable into different positions of adjustment by the interposition of the work between said abutment and said support, means operated by a relative movement of said support and said carrier for locking said support to said carrier, 10 and means for thereafter moving said support and said carrier together.

25. In a machine of the class described, a work abutment, a work support, a movable carrier for said work support upon which 20 said work support is yieldingly adjustable as the work is interposed between said abutment and said support, means rendered operative by the movement of said carrier for locking said support to said carrier, and 25 means operating through said carrier for placing a predetermined clamping pressure upon the work after said locking operation.

26. In a machine of the class described, a work abutment, a work support, a movable carrier for said work support upon which 30 said work support is yieldingly adjustable as the work is interposed between said abutment and said support, means rendered operative by the movement of said carrier for locking said support to said carrier, means operating through said carrier for placing a predetermined clamping pressure upon the work after said locking operation, and means 35 for locking said carrier rigidly against movement after said predetermined clamping pressure has been applied.

27. In a machine of the class described, a work support, a carrier upon which said work support is self-positioning to accommodate its position to the thickness of the work, connections between said parts tending normally to maintain those parts yieldingly in extended relation, a work abutment, 45 means for automatically locking said work support to said carrier in the relation which said parts assume as determined by the thickness of the work, and means for thereafter effecting final work clamping relationship between the work support and said 50 abutment.

28. In a machine of the class described which comprises mechanism for performing a series of operations upon work and means for effecting a relative feeding movement of 60 the work and said mechanism between successive operations, the combination with a work support comprising members relatively movable to adjust the support to different work thicknesses, of means comprising interlocking parts carried by said members for

automatically effecting such relative movement and locking said members in the position of adjustment for said series of operations before said operating mechanism begins to operate upon the work.

29. In a machine of the class described which comprises mechanism for performing a series of operations upon work and means for effecting a relative feeding movement of the work and said mechanism between successive operations, a work support, a carrier for said work support, means for moving said carrier from work-receiving to work-clamping position, and connections between the work support and carrier permitting movement of the work support relatively to the carrier to adjust the work support to different thicknesses of work and comprising means to lock the work support to the carrier in adjusted position for said 75 series of operations upon the movement of the carrier from work receiving position.

30. In a machine of the class described which comprises mechanism for performing a series of operations upon work and means for effecting a relative feeding movement of the work and said mechanism between successive operations, a carrier, a work support mounted on said carrier for movement relatively thereto, means for intermittently lowering the carrier to release the work for feeding between successive operations of said mechanism, means for effecting a final lowering movement of the carrier of greater extent than the work releasing movement to 90 permit the removal of the work from the work support, connections between the work support and carrier constructed and arranged to maintain the work support in interlocked engagement with said carrier during the work releasing movements of the carrier, and means to release the work support from locked engagement with the carrier upon the final movement of the carrier to work removing position.

31. In a machine of the class described, which comprises mechanism for performing a series of operations upon work and means for effecting a relative feeding movement of the work and said mechanism between 115 successive operations, a carrier, a work support mounted on said carrier for movement relatively thereto, means for raising said carrier from work receiving position, means for locking the work support to the carrier upon 120 movement of the carrier, means for releasing said locking means, means for lowering the carrier and work support intermittently to permit relative feeding movement of the work and said mechanism between successive 125 operations of said mechanism and means for automatically moving said releasing means to a position out of the path of movement of the locking means and maintaining the releasing means in such position during 130

the performance of a series of operations by said mechanism.

32. In a machine of the class described, a carrier, a work support slidably mounted on said carrier, means mounted on said carrier and work support for locking the work support to said carrier, means for moving said carrier to and from work receiving position, and means engaged by said locking means upon movement of the work support to work receiving position and operating to unlock the work support from the carrier.

33. In a machine of the class described, a carrier, a work support slidably mounted on the carrier, means for locking the work support to the carrier comprising interlocking parts carried by the work support and carrier constructed and arranged to be normally in locked engagement with each other, means for moving said carrier to and from work receiving position, and means operating upon movement of said carrier to work receiving position to unlock the work support from the carrier.

34. In a machine of the class described, a carrier member, a work supporting member slidably mounted on said carrier member, means for locking the work supporting member to the carrier member comprising cooperating parts carried by said members and

means mounted on one of said members for maintaining said parts normally in locking relation to each other, means for moving said carrier member to and from work receiving position, and means operating upon movement of said carrier member to work receiving position to unlock the work supporting member from the carrier member.

35. In a machine of the class described, a carrier member, a work supporting member slidably mounted on said carrier member, means for locking the work supporting member to the carrier member comprising teeth formed on one of said members and a pawl carried by the other of said members normally maintained in locking relation with said teeth, means for moving said carrier member to and from work receiving position, and means operating upon movement of said carrier member to work receiving position to disengage the pawl from said teeth and unlock the work supporting member from the carrier member.

In testimony whereof I have signed my name to this specification in the presence of two subscribing witnesses.

LOUIS A. CASGRAIN.
